LACE TRIMMING

James J. Holt, New York, N. Y., assignor to Jay-holt-Barbizon Corporation, New York, N. Y., a corporation of New York

Application July 17, 1948, Serial No. 147,636

Term of patent 3½ years

(Cl. D92—1)

To all whom it may concern:

Be it known that I, James J. Holt, a citizen of United States of America, residing at New York city, in the county of New York and State of New York, have invented a new, original, and ornamental Design for a Lace Trimming, of which the following is a specification, reference being had to the accompanying drawing, forming part thereof.

The figure on the drawing is a front view of a lace trimming, showing my new design.

I claim:

The ornamental design for a lace trimming, as shown.

JAMES J. HOLT.
